L. G. EDDY.

PUMP CYLINDER.

APPLICATION FILED APR. 9, 1913.

1,090,037.

Patented Mar. 10, 1914

UNITED STATES PATENT OFFICE.

LORENZO GILBERT EDDY, OF HUNTINGTON, NEW YORK.

PUMP-CYLINDER.

1,090,037.

Specification of Letters Patent. Patented Mar. 10, 1914.

Application filed April 9, 1913. Serial No. 759,980.

To all whom it may concern:

Be it known that I, LORENZO GILBERT EDDY, a citizen of the United States, and a resident of Huntington, in the county of 5 Suffolk and State of New York, have invented a new and Improved Pump-Cylinder, of which the following is a full, clear, and exact description.

The invention relates to driven wells and 10 its object is to provide a new and improved pump cylinder arranged for convenient removal from the well casing whenever it is desired to repair or clean the screen or other part.

15 For the purpose mentioned, use is made of a sleeve extending into the lower end of the pump cylinder and provided at its lower end with a screw thread, a screen, a coupling removably connected with the said sleeve 20 and with the said screen, and a packing on the sleeve intermediate the said pump cylinder and the said coupling.

A practical embodiment of the invention 25 is represented in the accompanying drawings forming a part of this specification, in which similar characters of reference indicate corresponding parts in all the views.

Figure 1 is a side elevation of the pump cylinder in position in the well casing, the 30 latter and barrel being shown in section; Fig. 2 is a sectional side elevation of the same; Fig. 3 is a sectional plan view of the same on the line 3—3 of Fig. 2; Fig. 4 is a perspective view of the sleeve; and Fig. 5 is a side elevation of the tool for removing the 35 sleeve.

In pump cylinders as heretofore constructed, it frequently happens that the pump cylinder cannot be removed from the 40 well casing in case it is desired to repair or clean the screen or other part. This is mainly due to the packing action of the sand which lodges between the barrel and the well casing on top of the rubber packing held exteriorly on the cylinder and snugly fitting the interior surface of the well casing.

In order to release this sand and to allow 45 removal of the pump cylinder is the object of the invention presently to be described in detail.

The barrel A, shown in the drawings, is provided at its lower end with the usual retaining ring B supporting a check valve C, of any approved construction, and held 50 in the lower end of the barrel A. In the up-

per portion of the barrel A is mounted to reciprocate the usual plunger valve (not shown) for pumping the water in the usual manner. The barrel A extends in the lower portion of the well casing or tubing D, preferably provided at its lower end with the usual shoe E, and in order to hold the barrel A in position in the casing D use is made of a rubber ring F fitting snugly against the inner surface of the casing D. The rubber packing F encircles a sleeve G provided at its lower end with an exterior screw thread G' on which screws a coupling H held on the upper end of a screen I of usual construction, and through which the water 70 is drawn on actuating the plunger valve previously mentioned. The upper edge of the packing F abuts against the lower edge of the retaining ring B while the lower edge of the said packing F is engaged by an inferiorly threaded metallic washer J resting on the upper end of the coupling H so that the rubber packing F is properly expanded in an outward direction so as to fit snugly 75 against the inner surface of the well casing D to securely hold the barrel A in position in the lower end of the well casing D. The upper end of the sleeve G is provided with bayonet slots G² adapted to be engaged by a suitable tool K such as shown in Fig. 5, to 80 permit of turning the sleeve G with a view to screw the same in or out of position on the upper end of the coupling H. The lower end of the retaining ring B is provided with an interior screw thread B' in 85 which is adapted to screw the screw thread G' at the time the sleeve G is turned to unscrew out of the coupling H, the washer J and the packing F.

The operation is as follows: Presuming 90 that the barrel A is stuck in the well casing D by sand lodged between the exterior surface of the barrel A and the inner surface of the well casing D, the downward movement of the sand being checked by the packing F, the operator first removes the plunger valve in the upper end of the barrel A and then removes the check valve C, after which the tool K is lowered into the barrel A and engaged with the bayonet slots G² 100 to permit of turning the sleeve G with a view to unscrew the same from the coupling H and to unscrew the same out of the washer J, packing F and thread B' to allow of finally lifting the sleeve G out of the 110

cylinder and out of the well casing. It will be noticed that when the sleeve G is removed the previously expanded packing F relaxes owing to its elasticity, and consequently 5 the sand between the barrel A and the well casing D is released to allow convenient pulling up of the barrel A by now screwing the lifting rod into the lower threaded end B' of the retaining ring B and then lifting 10 the said rod. The lifting rod may next be screwed into the coupling H to lift the screen I, packing ring F and washer J. By the arrangement described the barrel A need not be turned when removing it from the 15 well.

It is understood that when the sleeve G is unscrewed, the screen I and its coupling H are held against turning by the sand in which the screen I is embedded, and hence 20 the sleeve G can be readily unscrewed from the coupling H and the lifting rod previously mentioned can be subsequently readily screwed into position in the upper end of the coupling H.

25 Having thus described my invention, I claim as new and desire to secure by Letters Patent:

1. In combination, a pump cylinder, a sleeve extending into the lower end of the 30 pump cylinder and provided at its lower end with a screw thread, a screen, a coupling removably connected with the said sleeve and with the said screen, and a packing on the sleeve intermediate the said pump cylinder 35 and the said coupling.

2. In combination, a pump cylinder, a sleeve extending into the lower end of the pump cylinder and having bayonet slots for engagement by a turning tool, a rubber 40 washer encircling the sleeve below the said cylinder, a screen, and a coupling screwing

on the lower end of the sleeve and the upper end of the screen.

3. In combination, a pump cylinder, a sleeve extending into the lower end of the 45 pump cylinder and provided at its lower end with a screw thread, a screen, a coupling removably connected with the said sleeve and with the said screen, and a packing on the sleeve intermediate the said pump cylinder 50 and the said coupling, the said packing being made in the form of a rubber ring having a lining of sheet metal encircling the sleeve.

4. In combination, a pump cylinder provided at its lower end with a retaining ring 55 for the suction valve, a sleeve extending with its upper end into the said retaining ring and having an exterior screw thread at its lower end, the said upper end being provided with bayonet slots adapted to be engaged by a turning tool, a screen provided 60 with a coupling adapted to screw onto the lower threaded end of the sleeve, an elastic packing ring encircling the said sleeve above, 65 its screw thread, the upper edge of the said packing ring abutting against the lower edge of the said retaining ring, a metallic washer encircling the said sleeve and engaging 70 the bottom edge of the said packing ring, and a screen having a coupling screwing onto the said lower threaded end of the said sleeve and engaging the said metallic washer.

In testimony whereof I have signed my 75 name to this specification in the presence of two subscribing witnesses.

LORENZO GILBERT EDDY.
